Charles R. Searle.

UNITED STATES PATENT OFFICE.

ELMER E. TAGGART, OF SYRACUSE, NEW YORK.

LIGHTING DEVICE.

1,212,711.

Specification of Letters Patent. Patented Jan. 16, 1917.

Application filed May 20, 1916. Serial No. 99,000.

To all whom it may concern:

Be it known that I, ELMER E. TAGGART, a citizen of the United States, residing at Syracuse, in the county of Onondaga and 5 State of New York, have invented a certain new and useful Improvement in Lighting Devices, of which the following is a specification.

The invention relates to igniters of that 10 class in which a sparking metal or alloy is momentarily acted upon by an abrading surface to produce a flow of sparks directed into a stream of gas or vapor issuing from an adjacent burner, and relates more particularly to the mechanism for actuating the 15 abrading element.

The object of the invention is to provide 20 simple, easily operated means whereby an abrading wheel may be caused to rotate in one direction only in the production of the desired shower of sparks, thus lessening the wear on the alloy due to idle movements of such wheel in the opposite direction, and which shall consist of few parts capable of 25 being economically manufactured and assembled.

The invention consists in certain novel 30 features of arrangement and details of construction by which the above objects are attained, to be hereinafter described and claimed.

The accompanying drawings form a part 35 of this specification and show an approved form of the invention.

Figure 1 is a side elevation showing the 40 improved lighter attached to a burner. Fig. 2 is a corresponding plan view. The remaining figures are on a greatly exaggerated scale and show the sparking mechanism alone. Fig. 3 is a vertical section. Fig. 4 is a horizontal section taken on the line 4-4 in Fig. 3. Fig. 5 is a similar section taken on the line 5-5 in Fig. 3, and partly in plan view.

Similar letters of reference indicate the 45 same parts in all the figures.

A is a burner, shown as adapted to serve with acetylene, and mounted upon a suitable fixture, not shown.

B is a tubular casing having arms B¹ extending laterally therefrom, shaped to encircle the base of the burner and be clamped firmly thereto by a bolt B² and thus support the casing firmly in a vertical position parallel with and adjacent to the burner. The 55

casing B carries the igniting mechanism and its operating means.

Within the casing at its upper end is fixed a collar C having a central opening c, and at the lower end is a plug D loosely mounted 60 within the casing and having a radial arm D¹ extending through a circumferential slot b in the casing and carrying a head or knob D² by which the plug may be partially rotated or oscillated in the casing to an extent 65 determined by the length of the slot b.

F is a rod extending axially of the casing B, through the opening c in the collar C and projecting above the upper end of the casing. At the lower end the rod is fixed axially in the plug D to rotate therewith, and immediately above the plane upper face of the collar C is a disk or clutch member, G, to be described, fixed on the rod; above this clutch member G is the abrading wheel H 75 having its edge roughened, and carrying a depending annular flange H¹ inclosing the clutch member and overlapping upon and inclosing the extreme upper end of the casing B. The abrading wheel H is loosely 80 mounted on the rod F and is retained thereon by the head F¹ formed by upsetting the end of the rod.

On a bracket J¹ secured to the upper end 85 of the casing B, is a tube or carrier J extending radially from the wheel H with its inner end lying close to the latter. The carrier receives a short cylinder or pencil M of the sparking material and presents it to the roughened edge of the wheel in position to 90 be acted upon by such abrading surface, and the carrier J is so located angularly relatively to the vertical plane of the burner and casing as to direct the tangential stream of sparks approximately to the center of the 95 burner when the wheel is partially rotated in the direction of the arrow in Fig. 2.

The exposed end of the pencil M is held 100 in strong frictional contact with the wheel H by the expansive force of a helical spring J² inclosed in the carrier J and abutting at one end against the pencil M and at the other against a screw plug J³ by which the tension of the spring may be varied, or increased as the length of the pencil is reduced 105 by abrasion.

The clutch member G is a disk fixed on the rod F and has in its edge a series of notches deeply cut at one end, bounded by the radial wall g, and diminishing in depth 110

2
toward the periphery, by the curved wall g^1 . Each notch receives a rolling member which may be a ball but is shown as a short vertical roller L adapted to coact with the inner 5 face of the annular flange H^1 of the wheel H and engage such flange when forced into the angular space between the flange and the curved wall g^1 of the recess or notch. The deep ends of the notches, determined by the 10 length of the radial walls g , are large enough to permit the member G to be rotated in one direction and carry the rollers L idly without engaging the flange H^1 , and the wheel H remains stationary held by the engagement 15 therewith of the pencil M, but a return movement, in the opposite direction, crowds the rollers into the narrowing portions of the notches and into close frictional engagement with the flange H^1 and thus compels 20 the latter and its wheel H to rotate.

N is a helical spring encircling the rod F, inclosed in the casing B, and having at its upper end an arm N^1 received in a recess or hole c^1 in the fixed collar C, and an arm N^2 25 at the lower end received in a recess d in the loose plug D, and arranged to resist by its torsional force the rotation of the rod F in one direction, and when thus forcibly turned and released, to return the rod rapidly to the 30 original position carrying with it the wheel H through the action of the clutch member G and rollers L with the flange H^1 .

In operating the lighter the arm D^1 is 35 forced by the fingers to a position at or near the end of the slot b , this movement increases the tension of the spring N and partially rotates the clutch member G, the wheel H remaining stationary; the arm D^1 is then suddenly released, the spring N asserts itself 40 and induces a sharp return movement, partially rotates the rod F and through the engagement of the rollers L with the flange H^1 causes a rapid partial rotation of the wheel H in contact with the pencil M and 45 produces the desired stream of sparks.

Each operation presents a fresh peripheral portion of the abrading wheel to the pencil, and the clutch mechanism employed 50 obviates the complications due to vertical movements of the parts, thus permitting the structure to be simplified and accomplishing a corresponding saving in the cost of manufacture.

I claim:

55 1. In a device of the character set forth, a loosely mounted rotatable abrading wheel, a carrier adapted to present a body of sparking material thereto in frictional contact therewith, an annular flange on said wheel,

a clutch member inclosed by said flange and 60 having angular peripheral notches, rolling members in such notches adapted to move idly with said clutch member and out of engagement with said flange when said clutch member is rotated in one direction, 65 and to coact with said clutch member and engage said flange and rotate said wheel when said clutch member is rotated in the opposite direction, manually operated means for partially rotating said clutch member in 70 such one direction, and spring actuated means for partially rotating said clutch member in such opposite direction when such manually operated means is released.

2. In a device of the character set forth, 75 a loosely mounted rotatable abrading wheel, a carrier adapted to present a body of sparking material thereto in frictional contact therewith, an annular flange on said wheel, a clutch member inclosed by said flange and 80 having angular peripheral notches, rolling members in such notches adapted to move idly with said clutch member and out of engagement with said flange when said clutch member is rotated in one direction, and to 85 coact with said clutch member and engage said flange and rotate said wheel when said clutch member is rotated in the opposite direction, manually operated means for partially rotating said clutch member in such 90 one direction, and a torsional spring opposing such manual rotation and serving to rotate said clutch member in such opposite direction when said manually operated means is released. 95

3. In a device of the character set forth, 100 a tubular casing, a fixed collar therein at one end, a plug loosely inclosed in the other end, an arm on said plug extending through a circumferential slot in said casing, a torsional spring attached at one end to said collar and at the other to said plug, a rod 105 fixed in said plug and extending axially of said casing and through said collar, a clutch member fixed on said rod and having angular peripheral notches, a rotatable abrading wheel loosely mounted on said rod, an annular flange on said wheel inclosing said clutch member, rolling members in such notches adapted to coact with said clutch 110 member and flange, and a carrier adapted to contain a body of sparking material and present it to said wheel in frictional contact with the latter.

In testimony that I claim the invention 115 above set forth I affix my signature.

ELMER E. TAGGART.
